COMBINED BOX OPENER AND DISPENSER
Theodore C. Kass and Jerry R. Kass, both of R.F.D. 2,
Ravenna, Mich.

Filed Apr. 3, 1961, Ser. No. 100,136
4 Claims. (Cl. 222—81)

This invention relates to a dispenser, and more particularly to a combined box opener and dispenser.

Although combined box openers and dispensers are previously known, they do not include the novel features of this invention. These improvements include the manner in which the sides of the dispenser body are shaped to form cutting edges on the sides thereof. These cutting edges cooperate with a blade formed on the bottom of the dispenser to sever the carton along a line parallel with the sides of the carton and along lines transverse to the side of the carton. The upwardly and outwardly diverging construction of the sides forces the portion of the carton severed downwardly and inwardly, providing for easy insertion of the dispenser.

It is therefore an object of this invention to provide a dispenser which is easily insertable in a carton.

Still another object of this invention is to provide a dispenser having a blade for cutting the carton in one direction and cutting edges formed thereon for severing the carton in a transverse direction to facilitate insertion of the dispenser in the carton.

Still another object of this invention is to provide a dispenser having resilient clips for retaining the dispenser on the carton after it has been inserted.

These and other objects and advantages will become more apparent upon reading the specification in conjunction with the accompanying drawings.

In the drawings:

FIG. 1 is a perspective view of the dispenser shown located over a carton, the severance lines being shown in phantom on the carton;

FIG. 2 is an end elevational view showing the dispenser inserted in a carton;

FIG. 3 is a cross-sectional view taken along the section lines III—III of FIG. 1;

FIG. 4 is a cross-sectional view taken along the section lines IV—IV of FIG. 1.

Basically, this invention relates to a dispenser which is also utilized to open a carton. The dispenser has a body which includes sides and a back. The sides are connected together at the bottom and diverge upwardly and outwardly, forming a V-shaped member. The ends of the sides are flared outwardly to form cutting edges. A cutting blade is affixed to the bottom of the sides. The front of the body is open and forms a flow path for the contents of the carton to enter the cavity formed by the sides and back. The top of the sides are connected to a collar which in turn is affixed to a top. The collar is extended above the top and forms a spout. The spout thus communicates with the body cavity. The top is also provided with resilient clip members which depend downwardly and overlie the body sides. A cap is hingedly connected to the top and may be pivoted to a spout covering position.

The dispenser assembly is designated generally as 10. The assembly includes the dispenser body 15, blade 26, collar 28, top 30, and cap 38.

Referring more specifically to the details of the invention, FIGS. 1, 3 and 4 best show the dispenser body 15.

The dispenser body 15 is generally V-shaped as viewed from the end in FIG. 1. This shape is obtained from side members or legs 16 and 20 which are connected together along their bottom edge and formed so as to diverge outwardly and upwardly. The ends of the side 16 are bent or flared outwardly to form cutting edges

2

17 and 18. The ends of side 20 are similarly designed to form cutting edges 21 and 22. The purpose for the cutting edges will be explained more fully hereinafter.

The V-shaped body back 23 is affixed to the sides adjacent the cutting edges 18 and 22. The back 23 is recessed slightly, as shown in FIG. 3, so that it does not interfere with the cutting edges. The front of the body is open, as best shown in FIGS. 1 and 3. The open front provides a flow path for material contained within a carton to enter the body cavity 24 formed by sides 16, 20 and back 23.

Affixed to the joined bottom edges or apex of sides 16 and 20 is a cutting blade 26. It is of the shape of the point of a conventional knife blade having an arcuate portion 26a and a straight portion 26b. The straight portion of the blade is in the same plane as the back 23. The arcuate portion of the blade starts from this plane and continues to the other end of the body 15. Thus, the blade 26 is of the same width as the bottom edges 20 of the sides. The blade is sharp to facilitate cutting of the carton.

A collar 28 is affixed to the top edges of sides 16 and 20. The collar 28 is a ringlike member and projects above the top edges of sides 16 and 20.

Affixed to the collar 28 is a top 30. The top 30 has a flat generally rectangular shaped platform 31 with a centrally disposed aperture which receives the upper portion of the collar 28. The portion of the collar 28 which extends above the platform 31 forms the spout 36. The top is affixed to the collar by conventional fastening means.

Formed integral with the platform 31 are side clips 32 and 34. The side clips 32 and 34 are formed from the top 30 by merely bending the end portions of the platforms 31 downwardly. The ends of the side clips 32 and 34 are shown crimped to increase the resiliency of the members and form a bearing surface which engages the side of the carton to retain the dispenser in position.

Although not shown, it is to be understood that within the broadest aspect of the invention the side clips 32 and 34 may be extended to a point just beyond the point of cutting blade 26. A flange of similar length may be extended from the end of platform 31 along the back 23 of the body. This flange would be placed on the top of the carton, as shown in FIG. 1 and the extended side clips on the sides to properly position the dispenser to be inserted in the carton.

A conventional cap 38 is affixed to one leaf of a hinge 39 which is also secured to the platform 31. The cap 38 may be pivoted to a position to cover the spout and to an open position.

Although the dispenser assembly 10 may be made from metal, it is to be understood that within the broadest aspect of the invention it can also be molded from plastic or similar material.

Operation

Cereal is normally enclosed in a wax paper bag, shown in phantom as 50, and placed inside the cereal carton 45 (FIG. 1). The fold of the sack is placed adjacent the top of the carton. Due to this fold of the sack 50, it is desirable to place the point of cutting blade 26 at a point somewhat below the top so as not to interfere with this fold. Thus, the point of cutting blade 26 is positioned at approximately the junction point of severance lines 46 and 48.

With the point of the cutting blade 26 properly positioned, pressure is applied to the top of the dispenser. The blade will puncture the carton 45 and the sack 50 and the arcuate cutting surface of the blade 26 will sever the carton and sack 50 along the severance line 46.

When the cutting blade is fully inserted, the severance line 46 will have been completed.

Continued pressure on the dispenser top 30 will result in the cutting edges 17 and 21 severing the carton 45 and package 50 along the severance line 47, and the cutting edges 18 and 22 severing the carton and package 50 along the severance line 48. Due to the upwardly and outwardly diverging shape of sides 16 and 20, the portion of the carton 45 and package 50 within the severance lines will be folded downwardly and inwardly as these members are cut. The dispenser is inserted until the top platform 31 rests against the carton.

The resilient side clips 32 and 34 will adjust to the particular thickness of the carton and the crimped bearing surface will bear against the carton to maintain the dispenser in position.

When the dispenser is fully inserted, the open front allows the material within the carton to flow into the body cavity 24. The collar 28, including spout 36, communicates with the body cavity 24. Thus, when the cap 38 is open, the material within the carton is free to flow into the body cavity 24 and out the spout 36. When the proper amount of cereal has been dispensed, the cap 38 is positioned to cover the spout 36 and the cereal may be stored. Since the dispenser top lies flat against the side of the carton 45, the carton may be stored as usual.

When the carton is empty, the dispenser is removed by merely pulling it out of the carton. The dispenser thereafter may be inserted in a new carton.

From the above description it is clear that the dispenser may be readily inserted in the carton. The arrangement of the cutting blade and the cutting edges in conjunction with the shape of the dispenser body provide novel means for inserting the dispenser in the carton by merely applying pressure to the top of the dispenser. The dispenser is constructed of a minimum number of parts and therefore provides a competitive article of manufacture. The dispenser, after being inserted in the carton, assumes a position which is almost flush with the side of the carton thereby facilitating storage. The design of the side clips provides a means for adapting the dispenser to cartons of different thicknesses; however, the resiliency of the side clips maintains the dispenser in position.

While a preferred embodiment of this invention has been described, it will be understood that modifications and improvements may be made thereto. Such of these modifications and improvements as incorporate the principles of this invention are to be considered as included

in the hereinafter appended claims unless these claims by their language expressly state otherwise.

We claim:

1. A dispenser for cartons comprising: body means; said body means having upwardly divergent sides and a back forming a cavity with an open front, the edges of said sides being outwardly flared to form cutting edges; a cutting blade at the apex of said sides; a top on said body, including a spout communicable with said cavity, whereby pressure on said top results in said cutting blade severing said carton in one direction and said cutting edges severing said carton in a transverse direction allowing insertion of said dispenser into said carton, and the severed flaps of said carton being depressed along said divergent sides with said open front being in full communication with material in said carton so that the material can be discharged through said spout.

2. A dispenser for containers comprising: a top having an outlet; a hollow generally V-shaped body having legs extending downwardly from said top to an apex and including an end opening between the legs and communicable with said outlet; a cutting means formed at the apex of said V-shaped body; and said legs each having a pair of flared cutting edges adapted to sever flaps from a container as pressure is applied to said top, with said legs causing depression of the severed flaps along the sides of the legs to provide free flow of material in said container through said end opening and out said top outlet.

3. The dispenser in claim 2 wherein the cutting means is a blade extension located at the apex of the legs of said V-shaped body.

4. A dispenser for containers comprising: a top having an outlet; a pair of side members extending from said top converging downwardly toward each other defining a cavity; at least one open end between said side members; and a blade extension along the apex of said converging side members, whereby flaps severed by said blade are depressed sideways by said side members so as not to interfere with flow of material through said open end and out said top outlet.
